UNITED STATES PATENT OFFICE.

HELMUTH PAUL MARTIN AND OWEN DAVID LUCAS, OF WESTMINSTER, LONDON, ENGLAND, ASSIGNORS TO M. L. EXPERIMENTAL LIMITED, OF WESTMINSTER, ENGLAND.

MACHINE GUN AND SIMILAR WEAPON.

1,412,252.

Specification of Letters Patent. Patented Apr. 11, 1922.

Application filed September 15, 1920. Serial No. 410,543.

(GRANTED UNDER THE PROVISIONS OF THE ACT OF MARCH 3, 1921, 41 STAT. L., 1313.)

To all whom it may concern:

Be it known that we, HELMUTH PAUL MARTIN and OWEN DAVID LUCAS, both subjects of the King of Great Britain, residing 5 at Vickers House, Broadway, Westminster, in the county of London, England, have invented certain new and useful Improvements in Machine Guns and Similar Weapons, for which we have filed applications in 10 Great Britain Mar. 24, 1916, Patent #124,777, Apr. 7, 1916, Patent #124,802, Mar. 24, 1916, Patent #127,033, and July 30, 1917, Patent #128,308, and in France Feb. 6, 1918, Patent #496,195, and of which 15 the following is a specification.

This invention relates to the control of machine guns and similar weapons firing electrically detonated ammunition and has for its object to provide improved means 20 for controlling the period of firing of machine guns. The invention is particularly applicable to aeroplanes or airships in which the gun is fired between the blades of the propeller.

According to this invention a gun is used 25 which fires electrically detonated ammunition and which is intended to be fired between the propeller blades in combination with means for electrically controlling the 30 period or instant of firing in accordance with the movement of the propeller.

As an example in an automatic gun, the following devices may be employed in combination:

(a) An electrically operated detonator in 35 the cartridge;
(b) An electric contact arranged in the breech mechanism or associated with this mechanism and adapted to be put in circuit 40 when the breech is closed, or by the final closing movement of the breech.

(c) An electric circuit or circuits including the detonator or the breech contact, or else the detonator and the breech contact, 45 and a firing interrupter switch by means of which firing proceeds every time the breech block is locked.

(d) A commutator or a generator situated on or associated with the engine or the 50 propeller, and provided with a make and break device which controls the electric circuit of the gun, the timing of the commu-

tator or of the generator being so arranged that the electric current passes only when one of the propeller blades is not in the line 55 of fire so that if the controlling switch is closed the firing of the gun will be delayed until the current passes which occurs when the propeller blade is no longer in the line of fire.

It will also be seen that a similar controlling mechanism may be applied to non-automatic guns which fire ammunition provided with electric detonators.

It is to be understood that all automatic 65 or repeating guns are included in the term machine guns or similar weapons.

If desired the necessary lag may be provided on the commutator to allow for the interval of time between the moment when 70 the electric circuit is closed and that when the bullet reaches the plane of the propeller; this lag may be automatically increased or decreased in accordance with the speed of the engine, for example by means of a governing device operating upon the switch member of the commutator.

The invention will now be described with reference to the accompanying drawings in 80 which:—

Figure 1 is a diagrammatic view which shows an arrangement of the electric circuits but in which the commutator is not shown.

Figure 2 shows a modified arrangement 85 of the circuits of Figure 1.

Figure 3 is another diagrammatic view showing an arrangement of the electric circuits when a commutator is employed.

Figures 4 and 5 are respectively a section 90 and an end view representing the improved construction of a cartridge provided with an electric detonator.

Figure 5^a is a diagrammatic view showing the connections which enable the detonation 95 to be effected by means of a metal wire which is heated and intended to be employed with a cartridge such as that described in the specifications of British Patents Nos. 124782 and 128298.

Figures 6 to 11 show a construction of breech mechanism as applied to a Lewis gun and intended for use in the present invention.

Figure 6 is a section of the bolt and the spade grip of a Lewis gun showing a portion of the improvements applied thereto.

Figure 7 is an end view of Figure 6 looking from the right.

Figure 8 is a section of the piston rod and of the improved modification of the latter.

Figure 8^a is a transverse section.

Figure 9 is a side elevation of the right hand end of Figure 8.

Figure 10 is a sectional end view of Figure 9, and

Figure 11 is an end view of Figure 9.

Figures 12 to 15 shew a construction for converting an existing machine gun into one for firing electrically detonated cartridges;

Figure 12 is a part section through the bolt of a Lewis gun with the casing partly removed,

Figure 13 is a part section in plan shewing the cocking handle with its insulated spring and contact and the fixed contact on the slide.

Figure 14 shews an alternative form of insulated striker.

Figure 15 shews an alternative method in which one insulated plunger is carried at the forward end of the bolt and a modified striker carried in the socket of the piston rod.

Referring to Figures 1 and 2, *a* is a cartridge provided with a detonator *c* (see Figures 4 and 5) operated electrically and fired by an electric circuit closed by the contact pin *d*. The contact closed by the breech mechanism of the gun is designated by *o*, *o*, this contact forming part of the primary or the secondary circuit. The firing switch is designated by *p* and the battery or course of current is designated by *q*. A trembler coil of suitable type is designated by *s*. In Figure 1 the breech contact *o*, *o*, is in the primary circuit and, in Figure 2, it is in the secondary circuit.

When a magneto is used, it may be connected directly to the propelling engine or to the propeller, and it may furnish the current necessary for ignition and itself contain the commutator.

Figure 3 shows an arrangement of circuits in which a commutator *b* is associated with the propeller *x* and is so arranged that the circuit is broken by the insulated segments *b*¹ when one of the propeller blades is in line with the gun the position of which is indicated by the cartridge *a*. A supplementary contact *o*¹ ensures a double make and break in order to avoid the striker pin becoming "alive" before the breech is closed.

The working of the gun will be readily understood from the preceding description and we will now proceed to describe one construction of cartridge and the improved breech mechanism suitable for carrying out the invention.

Referring to Figures 4 and 5, which show the improved cartridge, this is provided in place of the ordinary percussion cap, with a detonator which is operated electrically and which is constituted by a plug *c* of vulcanite 70 or other suitable insulating material which occupies the space in which the percussion cap is ordinarily inserted. The detonator is provided with a central metal pin *d* and its inner face is made concave or hollow 75 as is shown at *e*, so as to contain the fulminate of mercury.

The pin *d* lies opposite the anvil *b* which may be shortened; the part *a* forming the body of the cartridge is of usual construction. The arrangement is such that the cartridge is fired when the current passes to the central pin *d* to cause a spark to pass from this pin to the anvil *b*⁵ in the body of the cartridge which anvil constitutes the other 85 pole of the circuit.

The ordinary striker of the gun is removed and replaced by an electric contact arranged so as to close the circuit when the breech is closed.

The electric current may be furnished either by a magneto or by an accumulator and a trembler coil or other suitable device. The control of this circuit may be obtained by a push button or by a switch of any other form. It will be noticed that the normal period of the gun is in no way interfered with, as after the passage of the spark and the firing of the cartridge the gun takes its normal time to recoil and close the breech again. 100 the gun is maintained in the closed position until the electric circuit is established; it also continues to fire at the normal speed as long as the electric circuit remains closed.

In Figure 5^a is shown the connections in the case of a cartridge ignited by a heated metal wire.

Referring to Figures 6 to 11, the front end of the bolt *f*, through which the striker normally works, is lined in a suitable manner by means of an insulating material *g*. A steel tube *d* is connected rigidly to the guide ring *h* situated at the rear of the bolt. This tube is sufficiently long to pass, through a hole made in the spade grip *j* when the bolt is in its forward position. The tube *i* is mounted concentrically with the axis of the bolt *f* and moves backwards and forwards with it. The tube *i* is lined with hard fibre or some other suitable insulating material *g* which projects for about half an inch or more beyond the tube at the rear end beyond the gun as shown at *g*¹. This lining is continued forward through the guide ring so as to meet the insulating lining in the forward end of the bolt *f*. The axis of this insulating material is drilled out for its entire length and contains a long steel rod *k* the diameter of which is reduced towards the front end of the bolt so that when 115 120 125 130

it is level with the base of the bolt on which the head of the cartridge rests, it has a diameter of approximately one sixteenth of an inch. This rod, being situated in the 5 centre of the bolt, comes opposite the aforesaid detonator pin *d* mounted in the cartridge (see Figures 4 and 5). The piston rod *l* of the gun (see Figures 8 and 8^a), has its striker and the mounting for the same 10 removed and has fitted to it a tubular rearward extension *m* passing through a hole *j*¹ in the spade grip *j* and carrying on its outer end a spring plunger *n* carefully insulated from the tube *m* by the non-conducting material *g*. This plunger is situated in such a position that its axis is in line with that of the steel rod *k* which is contained in the interior of the extension 15 on the bolt *f*. The length of the extension *m*, the position of the spring plunger *n* and the amount of its compression are so adjusted that when the piston rod *l* has caused the bolt *f* to turn so as to lock it the end of the plunger *n* is situated a short distance 20 (say approximately five eighths of an inch) from the end of the steel rod *k* in the bolt. As the piston rod *n* continues for the remaining inch of its forward movement, it brings the plunger into contact with the 25 steel rod *k* and moves this plunger some three eighths of an inch; it also in the last three eighths or half of an inch of its forward movement, connects the spring plunger *n* to one pole of the detonator current, the other pole being connected to any part 30 of the gun. The breech mechanism is provided with an auxiliary contact stud *y* arranged on the extension of the piston rod and adapted to come into contact with an 35 insulated spring pressed contact *z* mounted on the spade grip as is shown in Figures 6 and 7. The arrangement is such that the circuit is completed through the pin *d* of the detonator to the base of the cartridge 40 (see Figures 4 and 5) the circuit being established as shown in Figures 1, 2 or 3. It will be seen therefrom that neither the piston *n* nor the central rod *k* nor the piston rod are rendered "alive" until the piston 45 rod *l* has caused the bolt *f* to turn so as to lock the breech, the two contacts *n* and *y* which form a double break in the circuit being established or closed during the last three eighths of an inch or so of the movement 50 of the bolt, which forms part of the movement normally used for striking the percussion cap. In order that the gun may be easily converted, in case of need, from an electrically fired gun into a gun fired in 55 the ordinary way, the plunger *n* is provided with a loose saddle *r*, shown in Figures 9 and 11, which when it is in place prevents this plunger from being moved. The central rod *k* passing along the axis of the bolt 60 is always sufficiently free in this bolt, in the

direction of its axis, to permit of a free forward and rearward movement of about one sixteenth of an inch or thereabouts. It will be seen therefore that if the saddle is placed on the plunger as in Figure 11 so as 70 to prevent its compression; this plunger will then strike the central rod *k* with a force which is sufficient to enable this rod to be used as a hammer so as to detonate the percussion cap of ordinary ammunition. In 75 other words, the striker, instead of being in the interior of the bolt as at present, is removed to the rear end of the gun and acts through a loose firing rod *k* concentric with the bolt; the result of this is that the 80 gun can be instantly converted by placing the saddle *r* in position, from an electrically fired gun to a gun firing ordinary ammunition. When the gun is fired electrically, the ordinary trigger is held back out of 85 operation.

Referring to Figures 12 to 15 in which A represents the bolt of a Lewis gun, the existing striker is removed, and the socket B is bushed with insulating material C, and a 90 new striker D is fitted, adapted to move easily in the socket B and is held slightly forward, that is, towards the breech end E, by a light spring F. The whole of the striker D is insulated outside, except a fine point G 95 adapted to touch the cap of the cartridge when the breech is closed and locked.

Or the forward end of the striker D may be reduced in diameter, see Figure 12, so as not to make contact with the bolt A, the 100 latter may have a bush H of insulating material such as a gate or the like, recessed in its face, concentric with the cap or primer, and provided with a central hole J through which the striker D passes, a clearance hole 105 K being provided in the metal of the bolt behind the bush so that the striker does not touch the same during its forward and backward travel. A hole M is drilled through the arm N of the piston rod (not shewn) 110 which carries the striker socket B communicating between the socket and the slot O into which the cocking handle P fits. This hole M is also bushed with an insulating tube R the cocking handle P itself carries an insulated spring S adapted to press against a small rod T inserted in the hole M in the socket arm N which rod in turn presses against the portion of the striker D enclosed in the striker socket B, thus establishing a 115 connection between the cocking handle P and the striker D.

Alternatively, as shewn in Figure 15, through the insulating bush H may be mounted a spring pressed plunger or contact Y, adapted to be pressed by a plunger or striker D carried by the striker socket B of the piston rod and insulated therefrom, this plunger carrying current to the one situated in the bolt and making contact there- 120 125 130

with after the bolt is locked. In order to ensure contact between the rod T and the striker D we may provide a permanent flexible copper lead 2 soldered to striker at one end and to the insulated bush 3 at the other end.

The spring S on the cocking handle P has an insulated tongue V projecting sidewise, see Figure 13, adapted to make contact with a fixed contact W mounted on the gun and insulated therefrom, preferably attached to the locking slide X, and in such a position that the contact between the fixed contact W and the one Y on the cocking handle is made at the moment that the piston rod (not shewn) has travelled its full distance after closing the breech and rotating the bolt A. This fixed contact is connected by a suitable lead to one pole of the battery or generator, the other pole being directly connected to any part of the gun. The part marked Z represents a pin with a ball shaped head.

A means may be provided whereby on reversing the cocking handle so that the spring insulated contact is downwards in respect of the socket arm, an inclined plane pushes the contact rod upwards and locks the striker so that the light spring holding it forward cannot be compressed. In this position the striker is rigid in its socket and will therefore strike the cap with sufficient blow to detonate it by percussion in the usual way, thus instantaneously converting the gun from electric to percussion firing.

5 What we claim and desire to secure by Letters Patent of the United States is:—

1. The combination with a gun which fires electrically detonated ammunition and is intended to be fired between the blades of a propeller, of means driven from the engine of the propeller for electrically controlling the time of firing of the gun.

2. The combination with a gun which fires electrically detonated cartridges and is intended to be fired between the blades of a propeller, of an electric firing circuit for the cartridges and means driven from the engine of the propeller for controlling said circuit.

3. The combination with a gun which fires electrically detonated cartridges and is intended to be fired between the blades of a

propeller, of an electric firing circuit for the cartridges and a commutator driven from the engine of the propeller for automatically controlling said circuit. 55

4. The combination with a gun which fires electrically detonated ammunition and is intended to be fired between the blades of a propeller, of a magneto driven from the engine of the propeller for providing the electric current for firing and also for controlling the time of firing of the gun. 60

5. The combination with a gun which fires electrically detonated cartridges and is intended to be fired between the blades of a propeller, of an electric firing circuit for the cartridges, means driven from the engine of the propeller for automatically controlling said circuit and means whereby lag is automatically given to the first mentioned means. 65

6. The combination with a gun which fires electrically detonated cartridges and is intended to be fired between the blades of a propeller, of an electric firing circuit for the cartridges, means driven from the engine of the propeller for automatically controlling said circuit and a firing switch for manually controlling said circuit. 70

7. The combination with a gun which fires electrically detonated cartridges and is intended to be fired between the blades of a propeller, of an electric firing circuit for the cartridges, means driven from the engine of the propeller for controlling the time of firing of the gun, and an electric contact in said circuit, this contact being made each time the breech mechanism of the gun is closed and locked. 80

8. The combination with a gun which fires electrically detonated cartridges and is intended to be fired between the blades of a propeller, of an electric firing circuit for the cartridges, means driven from the engine of the propeller for automatically controlling the time of firing of the gun, an electric contact in said circuit, this contact being made each time the breech mechanism of the gun is closed and locked, and a firing switch for manually controlling said circuit. 90

In testimony whereof, we have hereunto affixed our signatures.

HELMUTH PAUL MARTIN.

OWEN DAVID LUCAS.
